UNITED STATES PATENT OFFICE.

CHARLES SILVERSTEIN AND SAMUEL SILVERSTEIN, OF BROOKLYN, NEW YORK.

IRONING ROLL.

Application filed June 16, 1925. Serial No. 37,555.

This invention relates to ironing rolls, and we would have it understood that in employing this term "ironing roll" we use the same in its broadest possible sense to include any device such as a cylinder, rotary member or other analogous device which may be used in connection with an ironing, calendering or other analogous machine.

The term "roll" is employed to avoid repetition in terminology but with a full understanding that such a term in its broadest possible sense.

An object of the invention is to provide a roll which is composed of a series of adjacent, individual, independently movable annular rings or members, each mounted on a common shaft, all being normally in alignment, yet each member individually capable of independent radial or lateral movement, thus presenting to any goods moved in contact with the roll, a uniform resilient surface, readily accommodating such irregularities as buttons, welts, hems and the like, without injury and without affecting the functioning of the remaining annular members composing the roll, and by this means, every part of all kinds and classes of goods is certain of receiving sufficient pressure, yet without injury, to insure a properly ironed finish.

It is a well known fact that rolls such as commonly employed cause the crushing of buttons and other similar irregularities in the thickness of any goods, and in general have various other defects which our improved roll overcomes, all of which will more fully hereinafter appear and be pointed out in the claims.

Thus, heretofore in order to give some semblance of resiliency to the commonly used one-piece roll, it has been a practice to utilize one or both of two expedients, namely, either the roll was given many extra thicknesses of fabric covering, or else the roll was cushioned on its supports at its extremities. Neither of these methods has ever given satisfactory results, as in the second method a poor finish is usually imparted to many goods, while in the first method the cost of maintaining the thick fabric covering is

very expensive and wasteful, both from the maintenance viewpoint on account of the high cost of fabric covering, and then again, this method is bad or inefficient from an operating viewpoint, as the great combined thicknesses of different layers of covering retard the quick evaporation and removal of the moisture and vapor liberated in the ironing process, inasmuch as the thick covering soon becomes compacted under the heavy pressure maintained, and also because such thick covering soon becomes soggy, and its meshes clogged with starch, sizing or lint, so that in a very short time, the covering becomes substantially useless from an operating viewpoint. In the present invention these difficulties are obviated, due to the individual and independent resiliency of each and every annular member composing the roll, so that consequently only the smallest possible amount of covering is requisite in order to give a proper finish to any goods being ironed.

It is therefore a further object of the invention to overcome such defects in present rolls as enumerated above, and to permit a substantial reduction in the thickness of the covering required on the periphery of the ironing rolls.

A still further object of the invention is to provide a large condensing surface in a roll to effectively condense the vapor and moisture liberated in the ironing process, with the view of more readily facilitating the removal of such moisture and vapor.

Another object of the invention is to provide a means by which any covering may be placed separately and independently on each individual annular member composing the roll, with the purpose of providing a means of allowing a freedom of movement to the individual annular member and with the purpose of providing a cheaper and more efficient method of maintaining the covering usually placed on the periphery of the ironing rolls.

Heretofore it has been the practice to mount on the periphery of the ironing roll a number of thicknesses of continuous widths of fabric materials, covering the full length

of the roll, so that if merely a small part of such covering was damaged, the entire sheet of covering would have to be removed or discarded with the consequent loss of much good material and time, whereas in the present invention, only that part of the damaged covering directly on the periphery of the individual annular member need be removed, the other undamaged parts of the covering on the remaining annular members being left intact and in place, thus saving material and labor, and insuring more productive ironing results.

Another object of the invention is to provide a resilient roll composed of a series of individual annular members, each of which is capable of being interchanged, replaced, assembled, or shipped with ease and readiness, and capable of being manufactured at a fractional part of the cost of spring padded rolls.

A still further object of the invention is to provide by means of a small free space between each of the individual annular members, and by means of grooves and perforations in the periphery of each individual annular member, a means to allow a more free passage for the escape and removal of moisture and vapor liberated in the ironing process. An efficient means is thus provided to maintain substantially dry throughout the entire ironing operation, any covering wound on the periphery of the roll.

In the accompanying drawings—

Figure 1 is a view in elevation, showing our invention as applied to a chest type of ironing machine;

Figure 2 is a similar view, showing the invention as applied to a cylinder type of machine;

Figure 3 is a view in transverse section through our improved roll, the view being taken on the line 3—3 of Figure 4;

Figure 4 is a broken view, partly in elevation and partly in longitudinal section, of one form of our improved roll;

Figures 5, 6, 7, 8 and 9 are views similar to Figure 3, illustrating modifications;

Figure 10 is a view similar to Figure 4, illustrating the roll illustrated by Figure 9;

Figure 11 is a fragmentary plan view, illustrating an assemblage of rolls;

Figure 12 is a fragmentary plan view, showing a modified form of roll;

Figures 13 and 14 are fragmentary views showing modifications.

Figure 15 is a view showing the annular members of the roll provided with narrow cover sections.

In Figure 1 we illustrate a series of our improved rolls 1 which co-operate with a chest 2 for the ironing of articles or material indicated by reference numeral 3.

In Figure 2 the rolls 1 are shown in connection with a cylinder 4, the material 3 be-

ing passed between the cylinder and the rolls, as is customary.

It is of course to be understood that heat is supplied in the ordinary manner and that our invention resides solely in the construction of the rolls themselves, which may be used in connection with the types of machine shown or with any other type of mechanism desired for the same or analogous uses.

Figures 3 and 4 illustrate in detail the preferred form of our improved roll.

5 represents a shaft which extends throughout the length of the roll and on which our improved ring elements 6 are secured. Each ring element 6 comprises an annular ring or outer portion which is connected by coil springs 7 with spokes 8 projecting radially from a hub 9, the hub being secured to the shaft, or at least turning with the shaft, and we may employ an ordinary key 10 for the purpose, although of course we do not limit ourselves to the particular manner of connecting the hubs to the shaft.

The spokes 8 are preferably located at 90° apart, and the springs 7 connect the outer ends of these spokes with perforated ears 11 on the annular ring member 6. It is to be understood that the springs are under sufficient tension so as to maintain the annular member concentric with the center or axis of the hub 9 so that when all the rings are in position on the shaft, they, being of the same external diameter, will present an outer surface or periphery which is normally in alinement or in register but each and every one of the annular ring members is capable of a radial or lateral movement when pressure is applied thereon, so as to allow the roll to ride over buttons or other enlargements without exerting injurious pressure either upon the enlargements or upon the rolls.

While the ring members are spaced slightly apart, this being somewhat exaggerated in Figure 4, to allow both a freedom of movement and also to provide a means for the escape or removal of moisture and vapor as it is liberated in the ironing process, the spacing may be varied to suit conditions.

Disks 12 of somewhat smaller diameter than the ring members 6, are also secured on the shaft 5 at the ends of the series of rings partially so as to form closures for the cylindrical structure thus provided, and also to act as a means of fixing and regulating the relative positions of the series of annular rings with the shaft.

Rolls of this type are commonly provided with some sort of covering (although when suitably polished may be used in some ironing or calendering processes without such covering) and it is to be understood that with our improved roll this covering can be in narrow sections 6* of a width equal or slightly less than the width of the annular

member to allow movement of the individual annular members, and also to serve such other purposes as have already been described herein.

5 In Figure 5 a modification is illustrated in which a pair of pivoted links 13 and 14 constituting a toggle joint connects the spokes 8 with the outer annular ring member 6 in addition to the coil springs 7.

10 In the modification illustrated in Figure 6 two pairs of links, constituting a double toggle 15, connect the spokes 8 with the ears 11 and have coil springs 16 connecting two of the pivots of said toggles so as to exert a pressure in a direction to expand the toggles and maintain the outer ring member in proper position.

15 In Figure 7 another modification is illustrated which is similar to Figure 6 with the exception that the coil springs 16 within the toggles are elongated and coil springs 17 outside of the toggles connect adjacent toggles to impart the same expansive movement to the spokes or connection between the hub and 25 the annular portion 6.

Figure 8 illustrates a modification which is similar to Figure 6 except that the toggles 18, corresponding to the toggle 15, are longer and the spokes 8 are shorter. The purpose 30 of the links is to provide additional connection between the annuli and the spokes, and prevents breaking of the springs under ordinary condition, and, in the event of such 35 breakage, they will provide a connection between the rims and the hubs and prevent the rims from falling down completely and hanging on the shaft.

40 In the modification illustrated in Figures 9 and 10, a cylindrical core 19 is provided, and the annular members 20, corresponding to the members 6, are each connected by radially positioned coil springs 21 directly with the hollow cylindrical core 19.

45 In Figure 11 we show in plan a series of these rolls 1 so as to illustrate the fact that the lines or spaces between the different annular ring member 6 are out of alinement or have a staggered relation, so that every 50 part of all goods coming in contact with our improved roll will be certain of receiving a perfect ironing finish.

55 In Figure 12 we illustrate a modification showing the annular ring members as perforated, as indicated at 21', and as grooved 60 as shown in Figure 13. The reason of the perforations and grooves is to facilitate the escape and removal of the moisture and vapor liberated in the ironing process; and in fact in all of the construction illustrated, 65 it will be noted that there is a small free space between each individual member of the series of rings composing the roll, thus allowing passage and free access to the interior of the roll of all moisture and vapor, and 70 from which interior all such vapor or mois-

ture may be exhausted or removed by means of suitable apparatus.

We illustrate in Figures 13 and 14 an annular member with a modification showing the surface of said annular member to be 70 corrugated, milled or otherwise given a slightly uneven or irregular surface, so that any covering wound on the periphery of said annular member may have a firmer and better grip or hold, thus avoiding any possibility of slippage of the covering. The annulus illustrated in Fig. 14 may also be provided with perforations as at 21'.

75 We would call particular attention to the fact that the disks 12 are capable of adjustment on the shaft so as to properly position the disks and permit of adjustment thereof. We have illustrated as means for rigidly securing said disks screws 25 which are projected through the hubs of the disks 80 and engage in any of a series of recesses 26 in the shaft.

85 It is obvious that a great many other modifications might be illustrated and described which carry out the broad idea of the invention which is to provide a roll made up or comprising a series of independently movable annular sections normally in alinement or in register but capable of movement radially or laterally or in fact slightly in any 90 direction to compensate for uneven surfaces over which the roll may pass or under which the material may be moved.

95 Furthermore, as above stated, the invention is not limited to any particular use although it is primarily adapted for the uses above explained, but we wish to cover the roll broadly for any use to which it can be put. By making the roll of independent 100 sections such as illustrated in Figures 3 to 105 8, inclusive, the sections can be removed and replaced at will and the roll can be made of any desired length.

110 While we have illustrated what we believe to be a preferred embodiment of our invention, it is obvious that various slight changes and alterations might be made in the general form of the parts described without departing from the invention and hence we do not limit ourselves to the precise details set 115 forth but consider ourselves at liberty to make such slight changes and alterations as fairly fall within the spirit and scope of the appended claims.

120 We claim:

1. An ironing roll comprising a rotary shaft, a series of normally peripherally alined independent elements mounted on said shaft, each element comprising a hub held to said shaft to rotate therewith and 125 an outer annulus and radially positioned coil springs connecting the hub and annulus, and adjustable end disks of slightly less diameter than the annuli, each of said disks being spaced from the adjacent annulus to 130

4
permit escape and removal of moisture and vapor from within the roll.

2. An ironing roll as in claim 1, characterized by the annuli providing means for the escape and removal of moisture and vapor liberated in the ironing process.

3. An ironing roll as in claim 1, character-

ized by the annuli being slightly spaced apart laterally to permit escape and removal of moisture and vapor liberated in the iron- 10
ing process.
